United States Patent Office.

HECTOR T. FENTON, OF PHILADELPHIA, PENNSYLVANIA.

Letters Patent No. 64,513, dated May 7, 1867.

IMPROVEMENT IN STEAM GENERATORS.

The Schedule referred to in these Letters Patent and making part of the same.

TO ALL WHOM IT MAY CONCERN:

Be it known that I, HECTOR T. FENTON, of Philadelphia, Pennsylvania, have invented certain improvements in Steam Boilers; and I do hereby declare the following to be a full, clear, and exact description of the same, reference being had to the accompanying drawing, and to the letters of reference marked thereon.

My invention consists of certain improvements in steam boilers, fully described and claimed hereafter, whereby a rapid generation of steam and thorough superheating of the same is insured and priming prevented.

In order to enable others skilled in the art to make and use my invention, I will now proceed to describe its construction and operation. On reference to the accompanying drawing, which forms a part of this specification,

Figure 1 is a vertical section of my improved steam boiler.

Figure 2, a transverse vertical section.

Figure 3, an exterior front view.

Figure 4, a plan view; and

Figure 5, a plan view of the inner flue.

A is the outer cylindrical casing or shell; B the inner casing, forming the central flue C; the two casings being connected together at the top by the annular plate *a*, and at the bottom by the casing *b* of the fire-place D, and the bottom plate *c* of the boiler. Within the inner casing B are arranged radially a number of vertical tubes, the upper and lower bent ends of which are so connected to the casing B that the tubes may have a free communication both above and below with the water-space of the boiler. The number of tubes E will of course depend in a great measure upon the dimensions of the casing B. On the top *a* of the boiler are secured four boxes, which are separated from the steam space of the boiler by plates *f* of wire gauze, or its equivalent, and from each box projects a pipe, G, communicating with a superheating vessel, H, which is situated directly above the central flue, and from which projects the steam pipe *e*. It should be understood that the boxes F, pipes G, and vessel H, are contained within a suitable casing, terminating in a flue through which the products of combustion are carried off to the chimney; this casing may be of the form represented by red lines, fig. 1. The fire-box is provided with a suitable grate, I, and with appropriate fire-doors, and the boiler has the other ordinary appliances, which it will not be necessary to enumerate. By the concentration of the products of combustion in the central flue, an intense heat is there produced, and to this heat are exposed the tube B and the vertical pipes E, the latter partially intercepting the products of combustion; hence there must be a rapid generation of steam at this point. As the superheating chamber is situated directly above the central flue, it must receive sufficient heat to effect the desired purpose; at the same time it is situated so far above the boiler that the access of water to the vessel by foaming is rendered difficult. Foaming, however, is rendered impossible by the boxes F and wire gauze or perforated plates *f*; for should any water gain access to the boxes it would be impossible for it to escape from the larger box into the smaller pipe. The number of boxes and pipes G may be greater or less than is shown, and, although I prefer a superheating chamber of spherical form, it may be of a different shape.

I claim as my invention, and desire to secure by Letters Patent—

1. The cylindrical boiler, its fire-box D, central flue C, and pipes E, the whole being constructed and arranged substantially as and for the purpose herein set forth.
2. The combination of the above, with a superheating chamber, H, situated above the central flue and communicating through pipes with the steam space of the boiler.
3. The boxes F, separated from the steam space by wire gauze, or its equivalent, and pipes G, less in size than the boxes.

In testimony whereof I have signed my name to this specification in the presence of two subscribing witnesses.

HECTOR T. FENTON.
